DUPLEX FRICTION ROLLER OPERATED
ENDLESS WEB CALENDAR

Neil D. Staley, Columbus, Ohio

Application September 26, 1945, Serial No. 618,633

1 Claim. (Cl. 40—118)

1

The present invention relates to devices known as perpetual calendars, the primary object of the invention being to provide a perpetual calendar embodying a casing having a sight opening, and endless webs movable before the openings, in such a way that the indicia on the webs will be displayed indicating the days of the months and months of the year.

An important object of the invention is to provide a device of this character including an endless web on which indicia indicating days of the week are provided, and another endless web operating adjacent thereto, and on which names indicating months of the year are provided, mechanism being provided for the operation of the webs, so that both webs may be operated by knobs located at a point intermediate the ends of the casing at the top thereof where they are readily accessible.

Still another object is to provide a calendar embodying independent endless webs, and independent means for operating the webs, the operating means for each web including stationary posts and friction-rollers to insure against the webs slipping when in operation.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings:

Figure 1 is a perspective view of a calendar constructed in accordance with the invention.

Figure 2 is a rear elevational view of the device, the rear closure having been removed.

Figure 3 is a sectional view taken on line 3—3 of Figure 2.

Figure 4 is a sectional view taken on line 4—4 of Figure 2.

Figure 5 is a sectional view taken on line 5—5 of Figure 2.

Referring to the drawings in detail, the casing of the calendar is indicated generally by the reference character 5, the front wall thereof being formed with a cut-out portion 6 which is closed by a transparent wall, providing a sight opening.

Disposed within the casing and arranged at a point intermediate the ends thereof, is the power-shaft 6', on which shaft is secured the friction-roller 7, the roller 7 being of a length to extend over substantially one-half the lengths of the

power-shaft. A nut indicated at 8 is provided on the power-shaft and contacts the upper end of the friction-roller 7, securing the friction-roller 7 to the shaft and at the same time providing a spacer for purposes to be hereinafter more fully described.

Cooperating with the friction-roller 7 is an idle friction-roller 9 which is mounted on the shaft 10 disposed vertically of the housing, the friction-roller 9 contacting the web 11 which moves between the rollers 7 and 9 to feed the web through the casing. This web 11 is formed with vertical lines defining columns 12 in which indicia are provided indicating the days of the week. The endless web 11 also operates over the vertical stationary posts 13 which are disposed within the casing at the ends thereof, the friction-roller 9 contacting the web adjacent to one of the posts 13 to grip the web and cause the web to be fed through the casing without buckling.

Mounted on the power-shaft 6' and extending into the casing, is a tubular shaft 14 which is provided with an operating knob 15 whereby the shaft may be rotated from a point exteriorly of the casing. Secured to the inner end of the tubular shaft 14 is a friction-roller 16 which is disposed adjacent to the idle friction-roller 17, the rollers 16 and 17 providing means to feed the endless web 18 through the casing so that the printed matter thereon will be displayed before the sight opening.

The web 18 also moves over the upper ends of the vertical posts 13 which act to prevent the web over-running, during the operation of the device to move the endless webs.

Pins 19 extend from the stationary posts 13 and provide stops adapted to contact with the upper edge of the web 11, while the lower edge of the web 18 contacts certain of the pins, holding the webs in their proper positions for alignment with the sight opening at the front of the casing.

A knob indicated at 20 is provided on the upper end of the power shaft 6, so that the power shaft may be rotated independently of the tubular shaft.

Positioned within the sight opening is a partitioning member 21 which is formed with a cut-out portion 22 providing an opening through which the printed matter on the web 18 may be viewed. This partitioning member also is provided with letters indicating the days of the week, so that when the endless web 11 is moved, certain dates of the month may be moved to

From the foregoing it will be seen that due to construction shown and described I have provided a perpetual calendar which may be readily and conveniently operated to indicate the dates of the days of the week and month, the operating mechanism and the endless webs of the device being such that the endless webs will be held flat at all times and will not buckle to cause any unsightly appearance.

What is claimed is:

A calendar of the class described comprising a casing having a display opening formed in the front wall thereof, vertical stationary posts having curved surfaces, mounted within the casing adjacent to the ends thereof, a vertical operating shaft disposed within the casing and being extended through the top of the casing, a friction-roller secured to the operating shaft and

extending throughout substantially one-half of the length of the operating shaft, a friction-roller operating within the housing adjacent to the roller secured to the operating shaft, an endless web having indicia formed thereon operating over the posts and adapted to move between said friction-rollers, feeding the web before the display opening, a tubular shaft mounted for rotation on the operating shaft and having one end thereof extending through the top of the housing, a friction-roller secured to the tubular shaft within the housing, an idle friction-roller contacting with the friction-roller mounted on the tubular shaft, an endless web carrying indicia operating over the posts and between the last-mentioned friction-rollers, whereby the latter web is moved before the display opening displaying indicia thereon.
